UNITED STATES PATENT OFFICE.

HENRY G. NEWELL, OF LE RAYSVILLE, PENNSYLVANIA.

BATTERY-SAVER FOR TELEPHONES.

1,253,084.

Specification of Letters Patent.

Patented Jan. 8, 1918.

Application filed July 3, 1916. Serial No. 107,412.

To all whom it may concern:

Be it known that I, HENRY G. NEWELL, a citizen of the United States, residing at Le Rayville, in the county of Bradford and State of Pennsylvania, have invented a new and useful Battery-Saver for Telephones, of which the following is a specification.

The present invention is a battery saver for telephones, and aims to provide a novel and improved stop or catch applicable to telephone instruments generally, and coöperable with the receiver or switch hook for holding it in intermediate position, with the battery transmitter and outside noises cut out, when the receiver is lifted from the hook.

The objects of the invention are made apparent by noting conditions prevailing in telephone practice, as follows: In local battery telephone service, the depletion or weakening of the battery is decidedly detrimental to strong and clear transmission and good service. This depletion of battery current, on party lines especially, results from eaves-dropping or listening in, and it also results legitimately from the time consumed in waiting for the line or distant connections. In noisy places there is also great gain to hearing if the transmitter and outside noises are cut out on listening and only cut in while talking. Long distance hearing is much improved and the local service also, as in party line service listening-in along the line introduces the nuisance of foreign noises, such as the crying of children, etc. The aforesaid losses of battery power and other disadvantages are largely responsible for poor service and considerable expense, not only for battery cells, but for livery hire and the time of the electrician in putting in new cells. Because of the foregoing objections, this invention was conceived to save the battery current and improve the service.

It is known that clumsy knife switches, push buttons, etc., have been used or resorted to, for the saving of battery current, but are more or less inconvenient and require special wiring and an electrician to install them properly, and are not entirely satisfactory, while certainly not universally applicable or convenient in use.

It is the primary object of the invention to meet the need of a device of the present character, using a device which is simple, convenient, and efficient in use, and provid-

ing a complete and attractive mail order specialty for telephones generally, the device being easily and quickly attached and accurately adjusted by any one of average intelligence. The present device is not only convenient in use, and natural in operation, but is perfectly reliable and not likely to get out of order with inexperienced users.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Fig. 1 is an elevation of the device as applied to a telephone set, a portion only of the set being illustrated, and portions being illustrated diagrammatically.

Fig. 2 is another elevation of the device, looking at right angles to the line of view in Fig. 1.

Fig. 3 is a sectional view taken on the line 3—3 of Fig. 2.

Fig. 4 is an elevation of a modification.

Fig. 5 is a plan view of the finger piece of the modified form shown in Fig. 4.

Fig. 6 is a sectional detail on an enlarged scale taken on the line 6—6 of Fig. 4.

Fig. 7 is an elevation of still another modification.

Fig. 8 is a section on the line 8—8 of Fig. 7.

Fig. 9 is an elevation of a fourth form.

Fig. 10 is a detail view of the bearing used in the device shown in Fig. 9.

Fig. 11 is a detail view illustrating a modified adjusting means.

Fig. 12 is a sectional detail showing another modified adjusting means.

In Fig. 1, a fragmental portion of a wall telephone set is depicted, the same including the box or casing 1 and receiver hook or fork 2 working within a slot in one wall of the box or cabinet 1. A spring contact 3 is connected with the hook 2 to be moved thereby, and forms a part of a circuit 4. The primary or local circuit 5 includes the battery 6 and transmitter 7, and has the terminal spring contacts 8 and 9 which when they are brought together close the primary circuit.

The contacts 3, 8 and 9 are normally separated when the receiver hook is lowered, and when the receiver hook is in intermediate position, the contact 3 engages the contact 8, while when the receiver hook is completely raised, the contact 3 raises the contact 8 with it against the contact 9. It is the function of the present device to hold the receiver hook in intermediate position whereby the receiver can be held to the ear for listening in on the line, for any purpose whatever, without the primary or local circuit 5 being closed, thus avoiding the wastage of current, and nuisance of outside noises, and with the advantage of cutting in and out instantly, simply and conveniently.

The present device as illustrated in Figs. 1, 2 and 3, embodies a pendant arm 10, formed of wire or other suitable stock, and formed at its upper end with coils 11 providing a bearing through which a nail or other pivot element 12 can be inserted to be driven into or otherwise engaged with the box 1 for pivotally hanging the arm 10 upon the outside of the box adjacent to the receiver hook, as clearly seen in Fig. 2.

Mounted adjustably on the arm 10 is a stop constructed of wire or other suitable material, and formed with close fitting coils 13 having a vertical axis, the wire being formed with a depending loop-shaped handle 14 at the lower end of the coils 13, and said coils being interiorly threaded and being screwed upon the arm 10 which is also threaded. The coiled nut or sleeve 13 is provided at that side adjacent the receiver hook 2 with an outstanding loop 15 overhanging the receiver hook, and providing the stop proper or catch, which is provided with the lower shoulder 16 adjacent the coiled nut 13 and the inclined or cam portion 17 at the outer end of the shoulder 16. The coiled nut 13 is provided with an outstanding loop-shaped finger piece 18, which in being disposed adjacent to the box 1, will prevent the nut 13 being unscrewed accidentally while the arm 10 is in place. The coiled bearing 11 has a horizontal axis perpendicular with the side wall of the box 1 whereby the arm 10 is swingable in a plane parallel with the box to and from the receiver hook 2. In one position of the arm 14, as seen in Fig. 2, the cam portion 17 is above the receiver hook 2, whereas if the arm 10 is disposed on the line $x-x$ in Fig. 2, the shoulder 16 will be over the receiver hook. The coils 11 provide an excellent bread bearing for the arm 10, and the coils 13 provide a relatively long threaded sleeve or nut which may have any desired degree of tension for gripping the arm or rod 10. The arm 10 can be readily attached to the box or other support of the cabinet at the proper point, whereby the arm will swing away

the stop or catch loop 15 from over the hook, either partially or completely. When the arm 10 is detached, it can be readily rotated with respect to the sleeve or nut 13 for adjusting the stop, whereby to properly hold the receiver hook in intermediate position when the stop is moved over the hook with the receiver off.

To provide a manually operated lock out and automatically restored device, the arm 10 is supported, as seen in Fig. 2, with the cam portion 17 normally over the receiver hook 2. Now, when a person desires to listen in on the line, as when waiting for a party called, or when listening for any purpose, when the receiver is taken off of the hook, the thumb or one finger of the hand (usually the left hand) which removes the receiver can be readily and naturally brought against the handle or thumb piece 14, to swing the arm toward the receiver hook, at the same time that the receiver is removed, thus bringing the shoulder 16 over the hook, and the hook in bearing upwardly against the shoulder 16 will prevent the hook from being completely raised. The hook will therefore be held in intermediate position, with the circuit 5 open. This saves the battery current and also cuts out the transmitter thereby avoiding unnecessary and troublesome noises on the line. Ordinarily, when the receiver hook is raised without touching the present attachment, the receiver hook 2 in engaging the cam portion 17 will deflect the stop out of the way. For the repeated cutting in and out of the battery and transmitter, as in exacting long distance conversation or other severe conditions, the horizontal thumb and finger piece 18 can be readily raised and lowered, or moved backward and forward alternately, which can be readily done by the right hand. Thus, when the arm 10 is moved away from the receiver hook, the receiver hook is permitted to move to raised position, and when the arm is moved toward the receiver hook, the cam portion 17 will depress the receiver hook to intermediate position, this operation being easily and quickly accomplished.

A second method of using the device is to position the arm 10 on the line $x-x$ in Fig. 2, whereby the shoulder 16 is normally over the receiver hook 2, thus providing an automatically and normally operative lock out and manually restored device, since when the receiver is taken off of the hook, the hook will strike the shoulder 16, thus holding the receiver hook automatically in intermediate position, and the arm 10 must be moved away from the receiver hook, to permit the receiver hook to move to its raised position.

The device shown in Figs. 4, 5 and 6, is constructed chiefly of a single length of wire or other suitable stock, and includes a

depending or vertical arm 10^a provided at its lower end with a loop-shaped handle or thumb and finger piece 14^a, while the arm 10^a is provided at its upper end with a doubled portion or loop 15^a. The wire is further bent to provide the outstanding loop-shaped stop or catch 15^a extending from the doubled portion 13^a, and providing a shoulder 16^a crossing the arm 10^a between its ends, that portion or terminal of the wire at that side of the arm 10^a opposite the stop 15^a providing an angular or L-shaped thumb and finger piece 18^a. The stop 15^a has the inclined cam portion 17^a, and that terminal 15^a of the wire which forms the handle 14^a has an eye 20 embracing the crossing portions of the wire. As a means for adjustably supporting the arm 10^a and its stop 15^a, a bearing block 11^a is fitted slidably within the doubled portion 13^a, and is apertured for the reception of the supporting pin or pivot 12^a, the head of which is preferably located within the doubled portion 13^a to assist in holding the bearing block and arm 10^a properly assembled. A clamping screw 19 is threaded into the block 11^a below the nail 12^a to clamp the doubled portion 13^a between the head of said screw and the block 11^a. When the screw 19 is loosened, the arm 10^a 30 can be adjusted vertically to adjust the stop 15^a.

The device shown in Figs. 7 and 8 is constructed from a strip of resilient metal or other suitable stock, and embodies a depending arm 10^b, the upper end of which constitutes one terminal of the strip and is provided with an aperture 11^b for the reception of the pivot for suspending the arm. The lower end of the arm 10^b is provided 40 with a doubled portion 14^b providing the depending handle, and from the doubled portion, the strip is bent and doubled to provide an outstanding horizontal handle or thumb and finger piece 18^b. The limbs of 45 the doubled portion 18^b are connected by a bolt and nut 19^b and the limbs of said portion have a tendency to separate. The strip extends from the portion 18^b across the arm 10^b to provide the shoulder 16^b forming a 50 stop for the receiver hook, and the other terminal of the strip forms an inclined cam portion 17^b extending from the shoulder 16^b. When the nut and bolt 19^b are tightened, the shoulder 16^b will be moved downwardly, and when the bolt and nut are 55 loosened, said shoulder 16^b can spring upwardly. The adjustment of the stop is therefore accomplished by adjusting the bolt and nut 19^b. The horizontal portion which 60 crosses the arm 10^b is preferably provided with notches 21, and the corresponding portion of the arm is of an angular or L-shaped section, as seen in Fig. 8, for engagement with the notches 21, to facilitate the adjust-

ment of the stop, since either of the notches 65 can be engaged with the arm 10^b.

In the form shown in Figs. 9 and 10, a vertical wire arm 10^c is provided with a lower loop-shaped handle 14^c, and the bent back portion has a coil 23 embracing the arm 10^c, 70 and said coil 20^c has a loop-shaped stop 15^c provided with the shoulder 16^c constituting one end of the wire. The suspending means for the arm 10^c is preferably constructed, in this case, from a piece struck from suitable 75 sheet metal and constituting a vertical nut or sleeve 13^c in which the upper terminal of the arm 10^c is threadedly or otherwise adjustably mounted, a horizontal bearing or sleeve 10^c at right angles with the sleeve 13^c, 80 and a web 22 connecting said sleeves and bracing them. The nail or pivot is insertible in the bearing 11^c for supporting the device. By rotating the arm 10^c, it can be adjusted vertically for adjusting the stop. 85

In the variation illustrated in Fig. 11, the upper end of the arm 10^c has a doubled portion 18^c extending at an angle to one side and provided opposite the arm 10^c with a bearing 11^c, and a screw 19^c or other suitable means 90 connects the limbs of the portion 18^c for adjusting them relative to one another, whereby to adjust the arm 10^c and its stop.

In the modification shown in Fig. 12, the arm 10^c is provided with a vertical slot 23 through which a horizontal spindle 16^c is passed to provide the stop or shoulder, one end of said spindle being bent to provide the inclined cam portion 17^c. The spindle 16^c is threaded through a pair of nuts 24 upon opposite sides of the arm 10^c, and one nut has a threadedly extending handle or finger piece 25 for rotating it. When the nuts are loosened the spindle 16^c can be adjusted vertically, and the nuts can be readily tightened to hold said spindle in its adjusted position. 100 105

The several forms above described each embody a substantially vertical arm or member having a stop for holding the receiver hook in intermediate position, and each form is naturally and conveniently operated by the thumb or finger of the left hand. Each form can be readily set for either the manual or automatic lock out of the battery, according to the two methods above described. The several forms can be quickly attached to the support, and precise adjustments of the stops can be made. The several forms are also very simple in construction, and provide for the instant cutting in and out of the battery and transmitter, for exacting long distance and other difficult conditions of conversation. Hearing is not interfered with in either the intermediate or upper position of the receiver hook by the operation of the present device, and the device can be conveniently manipulated by that hand 110 115 120 125

which is not holding the receiver. The devices are characterized by the facts that they are extremely simple, reliable, durable, convenient, neat, attractive, efficient, cheaply manufactured, readily attached, easily adjusted and universally applicable, thus providing a good mail order specialty. The devices are easily understood, attached and adjusted by the average individual, and are operated conveniently by the hand in removing the receiver.

Having thus described the invention, what is claimed as new is:

1. The combination with a casing and a receiver hook extending therefrom, of a pendant member pivoted at its upper end to the casing in a vertical line at one side of the receiver hook to normally hang in said line, and a stop carried by said member and projecting laterally therefrom to overhang the receiver hook, said stop having a cam portion above the receiver hook in the path thereof to swing said member away from the receiver hook when it is raised, the stop having a shoulder between said cam portion and member movable over the receiver hook when said member is swung toward it away from said vertical line, said member being free to swing toward and away from the receiver hook.

2. A device of the character described embodying a swingable member, and a member carried thereby and having a coiled portion embracing the first mentioned member and a stop extending from said coiled portion to engage over a receiver hook.

3. A device of the character described embodying a swingable member, and a member carried thereby having a coiled portion

embracing the first mentioned member and 40 provided with portions extending in different directions therefrom, one of the last mentioned portions providing a stop to engage over the receiver hook and the other providing a finger piece.

4. A device of the character described embodying a swingable member, and a member carried thereby embodying a coiled portion embracing it and having a loop extending 50 to one side and providing a stop to engage over the receiver hook.

5. A device of the character described embodying a swingable member, and a member carried thereby embodying a coiled portion 55 embracing it and having a loop extending to one side and providing a stop to engage over the receiver hook, and another loop extending in another direction and providing a finger piece.

6. A device of the character described embodying a member having a pivot at its upper end for suspending it in pendant position, and an adjustable member upon said member embodying a coiled portion threaded on the first mentioned member and having loops extending toward opposite sides, one providing a stop to engage over the receiver hook and the other providing a finger piece, said coiled portion having a loop depending from its lower end to provide a 70 second finger piece.

In testimony that I claim the foregoing as my own, I have hereto affixed my signature in the presence of two witnesses.
